CABINET FOR COMBINATION REFRIGERATOR AND FOOD FREEZER

William A. Arzberger North Syracuse, N. Y., assignor to Carrier Corporation, Syracuse, N. Y., a corporation of Delaware

Application January 3, 1955, Serial No. 33,812

Term of patent 3½ years

(Cl. D67—3)

The figure is a perspective view of a cabinet for combination refrigerator and food freezer embodying my new design. The other side not shown is substantially like the side shown.

I claim:

The ornamental design for a cabinet for combination refrigerator and food freezer, as shown and described.
